UNITED STATES PATENT OFFICE.

CHARLES C. HANSEN, OF EASTON, PENNSYLVANIA, ASSIGNOR TO INGERSOLL-RAND COMPANY, OF NEW YORK, N. Y., A CORPORATION OF NEW JERSEY.

HAMMER-DRILL.

1,084,270.

Specification of Letters Patent.

Patented Jan. 13, 1914.

Application filed February 23, 1909. Serial No. 479,324.

To all whom it may concern:

Be it known that I, CHARLES C. HANSEN, a citizen of the United States, and a resident of Easton, in the county of Northampton and State of Pennsylvania, have invented a new and useful Improvement in Hammer-Drills, of which the following is a specification.

This invention relates to improvements in hammer drills and is more particularly directed to certain improvements in rotation devices therefor.

The object of this invention is to provide a piston having its hammer extension provided with oppositely arranged spiral tongue and grooved connections with the rotation ring and the drill steel holding chuck respectively, thus permitting the drill to be made with fewer parts and more compact than heretofore and also permitting the oppositely arranged spiral tongue and grooved connections to be made with a less spiral turn than heretofore for a predetermined rotary movement of the drill steel.

In the accompanying drawings, Figure 1 represents a hammer drill in longitudinal central section showing one form of the invention, Fig. 2 is a similar view of a portion of the drill with the hammer piston removed, Fig. 3 is a transverse section taken in the plane of the line A—A of Fig. 1, looking in the direction of the arrows, and Fig. 4 is a transverse section taken in the plane of the line B—B of Fig. 1, looking in the direction of the arrows.

The hammer drill cylinder is denoted by 1 and its reciprocating piston by 2.

The drill steel is denoted by 3. The drill steel chuck 4 is rotatably mounted in a front extension 5 of the drill cylinder. The drill steel is locked to turn with the chuck in any desired manner, as for instance, by providing the drill steel with an angular portion and the chuck with an angular socket fitted to receive the said angular portion of the drill steel. The inner end of the drill steel 3 projects into an enlarged bore 6 at the inner end of the chuck 5 where the said drill steel may receive the impact from the hammer extension 7 of the piston 2.

A nut 8 is screwed into the enlarged bore 6 of the chuck, which nut has a tongue and grooved connection with the hammer extension 7 of the piston. A cylinder head 9 is interposed between the extension 5 and the

cylinder 1, through which head the hammer extension 7 is fitted to slide. A rotation ring 10 is located within the extension 5 adjacent to the head 9, which rotation ring is permitted a rotary movement in one direction and held against movement in the opposite direction by a pawl and ratchet connection with the extension 5, in the present instance by providing the ring with an annular series of ratchet teeth 11 and the extension 5 with spring pressed pawls 12. A nut 13 is screwed into the rotation ring 10 and has a tongue and grooved connection with the hammer extension 7 of the piston 2.

In the form shown, the hammer extension 7 is provided with oppositely arranged spiral tongue and grooved connections with the rotation ring and chuck, respectively, in the present instance by providing the nuts 13 and 8 of the rotation ring and chuck, respectively, with oppositely arranged spiral tongues 14, 15, fitted to enter oppositely arranged long and short spiral grooves 16, 17, respectively, formed in the hammer extension 7 of the piston. This oppositely arranged spiral tongue and grooved connection between the piston hammer extension and the rotation ring and chuck, respectively, will impart a step by step rotary movement in one direction to the drill steel 85 as the piston reciprocates, owing to the fact that the rotation ring is held against rotary movement in one direction while permitted to rotate in the opposite direction. By arranging these tongue and grooved connections in opposite directions, a predetermined amount of rotary movement to the drill steel may be obtained by a very small amount of turn in each of the spiral tongue and grooved connections and thus materially reduce the wear on the parts.

The rotation device for hammer drills, as herein shown and described, is very simple and compact and materially lessens the length of the tool by utilizing the piston hammer extension as a common means for providing a tongue and grooved connection with both the rotation ring and the drill steel chuck. Furthermore, the parts are so arranged that access thereto may be readily obtained for purposes of examination and renewal.

What I claim is:

1. In a hammer drill, a rotation ring, a hollow chuck and a piston having a reduced

hammer extension projecting through the ring into the bore of the chuck, said hammer extension having oppositely arranged spiral tongue and grooved connections with the ring and bore of the chuck, respectively.

2. In a hammer drill, a rotation ring having a nut, a chuck having a nut and a piston having a hammer extension provided with oppositely arranged tongue and grooved connections with the said nuts.

3. In a hammer drill, a rotation ring having a nut spirally tongued interiorly in one direction, a chuck having a nut spirally tongued interiorly in the opposite direction

13 and a piston having a hammer extension spirally grooved in opposite directions for engagement by the tongues on the first and second named nuts, respectively.

4. In a hammer drill, a cylinder, a cylin-

der extension, a cylinder head interposed between the cylinder and extension, a piston fitted to reciprocate in the cylinder and having a hammer extension fitted to reciprocate through said cylinder head, a rotation ring and a chuck mounted in said cylinder extension, the said piston hammer extension being provided with oppositely arranged spiral tongue and grooved connections with the rotation ring and chuck, respectively.

In testimony, that I claim the foregoing as my invention, I have signed my name in presence of two witnesses, this 13th day of February 1909.

CHARLES C. HANSEN.
